UNITED STATES PATENT OFFICE.

FRANK M. BURROWS, OF PITTSBURG, PENNSYLVANIA.

ERASER.

No. 823,918.

Specification of Letters Patent.

Patented June 19, 1906.

Application filed February 28, 1906. Serial No. 303,348.

To all whom it may concern:

Be it known that I, FRANK M. BURROWS, a citizen of the United States of America, residing at Pittsburg, in the county of Allegheny and State of Pennsylvania, have invented certain new and useful Improvements in Erasers, of which the following is a specification, reference being had therein to the accompanying drawings.

10 This invention relates to certain new and useful improvements in erasers; and the invention relates more particularly to type-writer erasers wherein a hard piece of rubber, such as sand-rubber, is employed for erasing ink.

Figure 1 is a side elevation of an eraser constructed in accordance with my invention. Fig. 2 is an edge view of the same. Fig. 3 is a side elevation of an eraser embodying my invention, showing a modified form of construction in which the eraser proper is detachably secured. Fig. 4 is an edge view of the same, and Fig. 5 is an enlarged fragmentary sectional view thereof.

25 My invention relates particularly to that form of erasers which are peculiarly adapted for use in connection with the erasure of type-written matter and in which the rubber member or eraser proper is secured in a holder, the said rubber member or eraser generally being in the form of a circular member or disk rotatably mounted in the holder, so that the entire periphery of the said rubber member or eraser proper may be presented for use in erasing.

30 In the illustration of my invention I have used that form of holder in which the rubber member or eraser proper, 1, is carried on a rivet 3, that is mounted in cheek-pieces 2 of the holder, the said cheek-pieces of the eraser holder or support in this type of construction having generally bound in their free end a plurality of bristles to form a brush 4. It is the usual practice in this type of eraser to 45 serrate the free ends of the metal cheek-pieces, as shown at 5, so as to firmly hold the bristles and rivet the said cheek-pieces together, as at 6, near their free end to bind them against the bristles. My invention 50 resides in forming the other ends of the cheek-pieces so as to produce finger-shields 7, this being accomplished by bending outwardly the part of the cheek-pieces, as shown, so that they lie at right angles to the remainder 55 of the cheek-pieces.

In the construction shown in Figs. 3, 4, and

5 the holder for the eraser member is of the same form as that shown in Figs. 1 and 2, the eraser member 8 being in this form of construction mounted on a removable screw 9 instead of on the permanent rivet 3, as shown in Figs. 1 and 2. By this construction I am enabled to renew the eraser member when necessary.

60 The specific type of eraser which I have improved is commonly known as the "Eberhard Faber Comet Eraser No. 1087;" but it is obvious that my improvement can be readily used in connection with the ordinary type of disk eraser wherein the depending supports or shields 2 and the brush 4 are dispensed with. My invention simply resides in bending the supports or shields 2 outwardly, as illustrated, whereby shields and supports will be provided for the fingers of a person using the eraser, 75 said shields and supports also preventing the paper upon which the erasure is being made from being smeared or injured by the person's fingers contacting with the paper. The construction of the shields 7 also lengthens 80 the life of the eraser and permits of practically the entire disk being used before the eraser in its entirety is discarded. Heretofore it was only possible to use the eraser-disk until it had reached the supports or shields 2 at which time it was necessary to discard the eraser. In connection with the eraser shown 85 in Figs. 3 and 4 the body portion of the eraser could be retained by inserting a new eraser-disk, and it will be observed that my improvement does not interfere with the removal of the disk through the medium of the screw 9 of said eraser.

90 A particular feature of my invention resides in the simplicity which does not necessitate an additional expenditure in the manufacturing of the erasers, as when the supports or shields 2 are being stamped the shields 7 can be simultaneously bent to the shape shown in the drawings.

95 I do not care to confine myself to any specific type of eraser or to the material from which the same is made.

100 Such changes in the size and minor details of construction as are permissible by the appended claims may be resorted to without departing from the spirit and scope of the invention.

105 What I claim, and desire to secure by Letters Patent, is—

110 1. In an eraser, the combination with supports or shields, of a disk eraser journaled be- 1707

- tween said supports, a brush mounted between said supports, the upper ends of said supports being bent outwardly to form protectors, substantially as described.
- 5 2. In an eraser, the combination with supports, of a disk eraser journaled between said supports, the edges of said supports being bent outwardly, to form shields, substantially as described.
- 10 3. The combination with supports, of a disk eraser mounted between said supports, said supports being bent outwardly to form shields, substantially as described.
- 15 4. The combination with a disk eraser, of supports arranged upon the sides of said eraser, and having their edges bent outwardly to form shields, substantially as described.
5. An eraser comprising a holder embody-
- ing cheek-pieces, an eraser member rotatably mounted between the cheek-pieces, and finger-shields carried by said cheek-pieces and extending outwardly at right angles thereto.
6. As a new article of manufacture, an eraser, comprising a flat eraser member, an eraser-member holder, embodying two separate spaced cheek-pieces between which the eraser member is held, and finger-shields carried by the cheek-pieces extending at right angles thereto.

In testimony whereof I affix my signature 30
in the presence of two witnesses.

FRANK M. BURROWS.
